UNITED STATES PATENT OFFICE

121,939

DESIGN FOR A TABLE CENTERPIECE

Cayetano Aguas, Long Beach, Calif.

Application March 11, 1940, Serial No. 90,819

Term of patent 14 years

To all whom it may concern:

Be it known that I, Cayetano Aguas, a citizen of the Philippine Islands, residing at Long Beach, in the county of Los Angeles and State of California, have invented a new, original, and ornamental Design for a Table Centerpiece, of which the following is a specification, reference being had to the accompanying drawing, forming a part thereof.

I claim:

The ornamental design for a table centerpiece, as shown.

CAYETANO AGUAS.
